UNITED STATES PATENT OFFICE.

MAX METZ, OF COVENTRY, ENGLAND.

APPARATUS FOR THE ELECTRIC LIGHTING OF MOTOR-CARS AND FOR OTHER PURPOSES.

1,084,220.

Specification of Letters Patent. Patented Jan. 13, 1914.

Application filed February 9, 1912. Serial No. 676,667.

To all whom it may concern:

Be it known that I, MAX METZ, a subject of the German Empire, residing at Coventry, in the county of Warwick, England, have invented new and useful Improvements in Apparatus for the Electric Lighting of Motor-Cars and for other Purposes, of which the following is a specification.

This invention has reference to switches for use in connection with electric batteries and though more particularly designed for electric lighting purposes is equally applicable where the current passing therethrough is put to other uses.

15 The object of the invention is to provide a switch which in addition to its function on the one hand as an electric distributor whereby the whole or one or more of a number of circuits may be completed or broken 20 at will, at the same time also serves on the other hand as a single or double pole switch and a change over switch whereby the battery may be changed from series working to parallel working.

25 The construction of the switch is further such that the various circuits which it controls may be supplied with current at different voltages from the same battery. For example, in the case of motor vehicles, the 30 head lamps which are required to give a powerful light are placed across the full battery voltage while the side lamps and tail lamp are placed across portions of the battery.

35 A switch constructed according to this invention comprises two series of insulated contacts between and adapted to make contact with which is a multiple brush or brushes.

40 The contacts and brushes are preferably inclosed in a dust and weatherproof manner in a casing of insulating material, the brushes being provided with an outside handle moving over a numbered or notched dial 45 so that the position of the brush or brushes relatively to the two series of contacts for any given effect may be determined.

The arrangement and working of the switch is such that one series of contacts 50 controls the battery while the other series of contacts regulates the lamp or other circuits to which the electric current is to be supplied.

Each of the battery series of contacts is 55 furnished with a terminal whereby it is per-

manently connected to a pole of the battery. The circuit series of contacts are likewise provided with terminals for connecting them to the various circuits.

The invention is described herein as applied by way of example to the lighting of motor vehicles though it is to be clearly understood that it is not limited to this application as it will be quite obvious that the invention is capable of application for other purposes.

In the accompanying drawings, Figure 1 is a general view of a switch constructed according to this invention and suitable for use in connection with the lighting of motor vehicles. Fig. 2 is a vertical section taken through the center of the complete switch. Fig. 3 is a plan of the multiple brush. Fig. 4 is a plan of the base plate carrying the circuit series of contacts. Fig. 5 is an underside plan view of the cover carrying the battery series of contacts. Figs. 6, 7, 8, 9, 10, and 11 are views similar to Figs. 4 and 5 illustrating the successive positions of the brushes for the different effects described.

Referring to the construction shown in Figs. 1 to 11 which is designed for use in the electric lighting of motorcars having, say, two head lamps, two side lamps and a tail lamp, 2 represents a base plate of insulating material carrying one of the two series of contacts, 3 a cover also of insulating material and carrying the other series of contacts, and 4 is a multiple brush whereby communication between the two series of contacts aforesaid may be made and broken in the manner hereinafter described. The terminal screws for the various contacts in the base plate and cover project from the back of the switch which is suitably recessed to accommodate their clamping nuts as shown in Fig. 2. The said brush comprises a block 4^a of insulating material mounted rotatably on a vertical spindle 5^a passing centrally through the switch, and radial arms or brushes proper 4^b which may be of laminated brass and are bifurcated at their outer ends as shown in Fig. 2 so as to make contact with the two series of contacts on the base plate and cover respectively.

The outer surface of the cover 3 is provided with a dial, Fig. 1, and the spindle is provided with an outside handle 5 moving over said dial so that the position of the brushes relatively to the two series of con-

tacts for any desired effect may be determined. A spring pin 6 carried by the block 4^a is adapted to engage in notches 7 in the cover 3 to retain the switch handle in any 5 position to which it may be moved.

The brushes and contacts are preferably inclosed in a dust and weatherproof manner by means of a short cylinder of glass, celluloid or other preferably transparent 10 material which is clamped between the cover and base plate as shown in Fig. 2.

The arrangement of the wiring is shown in Figs. 4 and 5 where it will be seen, Fig. 5, that each of the battery contacts *a*, *b*, *c*, and 15 *d* is provided with a terminal and when the current is obtained from a battery of six cells joined in series for example, the said battery contacts are of equal length and four in number, *a* and *d* being connected up 20 to the first and last cells of the battery while *b* and *c* are connected up to two terminals common to and joining the second and third and fourth and fifth cells respectively. The 25 brushes 4^b are also four in number and each about one quarter as wide as the length of a battery contact.

The circuit series of contacts, Fig. 4, which are like-wise provided with terminals, number five, *e*, *f*, *g*, *h* and *i* and, with the 30 exception of the fourth and fifth, *h* and *i*, which are of equal length are of graduated lengths, *e* and *f* being arranged so that the brush in its first position, Fig. 4, contacts with both of them.

35 The lengths of the circuit contacts are such that up to the fourth position of the switch handle Fig. 10, one of them is successively cut out of operation at each movement of the latter after which movement to 40 the fifth position (not shown) simultaneously cuts out both the fourth and fifth circuit contacts *h* and *i*.

The head lamps *H* are connected up in parallel between the first and last circuit 45 contacts *e* and *i* and receive the full voltage of the battery, Fig. 4, while the side and tail lamps *S*, *S'*, and *T* respectively are connected up between the second and third, *f* and *g* third and fourth, *g* and *h*, and fourth and 50 fifth *h* and *i*, contacts respectively as clearly shown in Fig. 4 and each receives the voltage of two cells of the battery.

The switch handle and brushes have five positions the first four of which are represented in Figs. 4 to 11. In the first position, Figs. 4 and 5 all the lights are on, i. e., the whole of both series of contacts are electrically connected by the four brushes, the first brush 4^b making contact with both 55 the first and second circuit contacts *e* and *f* as aforesaid. In the second position, Figs. 6 and 7, the first circuit contact *e* is cut out of operation thus breaking the head lamp circuit and leaving the side and tail lamps *S*, 60 *S'* and *T* on at the same voltage as before.

In the third position, Figs. 8 and 9 the second circuit contact *f* is cut out of operation leaving one side lamp *S'* and the tail lamp *T* alight the circuit joining up the first and last cells of the battery being now broken. 70 In the fourth position, Figs. 10 and 11, the third circuit contact *g* is cut out leaving only the tail lamp *T* alight, the circuits joining up the third and last circuit contacts and the second and fourth battery contacts being 75 now broken. In the fifth or "all off" position the fourth and fifth circuit contacts *h* and *i* are both cut out; the brushes for one or other of the two series of contacts being now 80 on the insulating portion of the switch.

The present invention also includes the construction of a switch which in addition to its function as a current distributor may also be used as a change-over switch so that the cells of the battery may be connected 85 up in series or in parallel according to the nature of the circuit, the chief advantage claimed being economy in the consumption of current. According to one way of carrying this into effect the battery contacts 90 are arranged in pairs in such a manner that for a portion of the total movement of the brushes each brush would contact with both members of each pair and afterward with only one of said members or vice versa or 95 both.

What I claim and desire to secure by Letters Patent is,

1. An electric switch for use in connection with electric batteries comprising a series 100 of insulated contacts, a battery, connections between the said battery and certain of said contacts, connections between intermediate parts of said battery and others of said contacts, a second series of contacts, connections 105 between the contacts of said second series adapted to form circuits with said first and second mentioned connections, a single switch handle, and a multiple brush operated thereby and adapted to make contact 110 with both of said series of contacts in such a manner that certain of the said circuits are supplied with current at less than the full voltage of the battery while at each successive movement of the switch handle 115 one or more of said circuits is or are cut out.

2. An electric switch for use in connection with electric batteries comprising a series of insulated contacts of equal lengths, a battery, connections between the said battery and certain of said contacts, connections between intermediate parts of said battery and others of said contacts, a second series of contacts of graduated lengths, connections between the contacts of said second series 125 adapted to form circuits with said first and second mentioned connections, a single switch handle, and a multiple brush adapted to be moved thereby in contact with both series of contacts in such a manner that one 130

or more of the said circuits may be made or broken at will and at the same time receive a current at different voltages from the same battery.

- 5 3. An electric switch for use in connection with electric batteries comprising in combination a base plate of insulating material, a series of contacts of graduated lengths carried thereby and adapted to be connected up
- 10 to a number of circuits to be supplied with the electric current, a cover plate of insulating material, a second series of contacts of equal lengths carried thereby some of which are placed across the full voltage of
- 15 the battery while the others are placed across a portion or portions of said battery,

and a multiple brush operated by a single switch handle for establishing electrical communication between the two series of contacts in such a manner that at each successive movement of said brush the whole or one or more of said circuits is or are cut out and at the same time receive current at different voltages from the same battery. 20

In testimony whereof I have signed my 25 name to this specification in the presence of two subscribing witnesses.

MAX METZ.
